UNITED STATES PATENT OFFICE.

WILHELM RESCH, DECEASED, LATE OF STEINEN, BADEN, GERMANY, BY ALFRED RESCH, ADMINISTRATOR, OF ZURICH, SWITZERLAND, ASSIGNOR TO GOTTFRIED SCHUMACHER, OF BASEL, SWITZERLAND.

APPARATUS FOR PACKING COPS FOR DYEING, BLEACHING, AND THE LIKE.

Application filed January 23, 1924. Serial No. 688,106.

To all whom it may concern:

Be it known that I, ALFRED RESCH, a citizen of the Swiss Republic, and resident of Zurich, Switzerland, am the administrator of the estate of WILHELM RESCH, late a resident of Stein, Baden, Germany, and late a citizen of the Swiss Republic, deceased, who has invented new and useful Improvements in Apparatus for Packing Cops for Dyeing, Bleaching, and the like, of which the following is a full, clear, and exact specification.

In dyeing cops on their paper tubes without central spindle it is well known to pack and press them in horizontal layers in a pack container and to drive thereupon the treating liquid through the cops in their longitudinal direction. This packing, however, has the drawback that in the alternate rows with a given number of cops there are formed on both sides dead spaces of a width corresponding to half a diameter of a cop, which cause an irregular treatment of the pack throughout, as the liquid, instead of passing through the cops at said zones, would be allowed to avoid same.

The present invention relates to improvements in apparatus for packing cops to be impregnated with a dyeing, bleaching or other liquid, wherein the pack container is combined with side filling bars arranged along the sides of the container and so shaped in cross section as to closely contact with the sides of the cop layers in order to close up any dead space that may result from a staggered arrangement of the cops in the layers. Such filling bars not only eliminate any free space along the layers, but also insure the correct position of the cops.

Preferably the pack container is provided on its front ends with lateral grooves extending down to its bottom and arranged to receive the ends of said filling bars so as to guide and hold them in their position, the said filling bars being thus locked against any transverse displacement.

The invention is illustrated in the accompanying drawings.

Fig. 1 is a vertical transverse section through a container with a pack of cops before its compression;

Fig. 2 is a plan view thereof and shows

the staggered row arrangement of the cops in the different layers;

Fig. 3 is a front view of the container (one front end being removed) to show the pack of cops when being compressed;

Fig. 4 shows in plan view a wider container with intermediate filling bars between separate sections of the cop layers;

Fig. 5 shows the two standard forms of side filling bars, while

Fig. 6 represents the two standard forms of said intermediate filling bars.

The packing of the container *a* is effected in such a way that at first two filling bars *b* of the form shown at I in Fig. 5 are laid on the right and left hand side upon the bottom of the container; then the cops *c* are placed in horizontal position side by side and by three rows lying behind one another between the said bottom bars *b*, whereby the cops of the different rows are in a staggered relation, see Fig. 2, the middle row comprising for example six adjacent cops and the two end rows having only five cops placed side by side. Thus, one layer of cops, the lowest one, is built up in the container *a*.

For the next upper layer, use is made of two filling bars *b*¹ of the shape represented at II in Fig. 5 along the right and left hand side of the container *a*, these filling bars *b*¹ having their thicker portion in the middle part, whilst the filling bars *b* of the said first or lowest layer have their thicker part at both ends. The cops are arranged between said filling bars *b*¹ in an analogous manner as in the lowest layer so that the middle row may comprise five cops side by side, whilst the end rows comprise each six cops side by side. For the next upper or third layer of cops, filling bars *b* of the shape shown at I in Fig. 5 are again employed and for the fourth layer of cops two filling bars *b*¹ of the shape shown at II in Fig. 5 are again used, and so on, the pack in the container being built up in the successive layers of cops alternately with the two forms of filling bars shown in Fig. 5, until the container is sufficiently charged.

All the filling bars that may be used are provided at their ends with studs *d* arranged to slidably engage into vertical grooves *e* provided on the inner side of the

front walls of the container *a*, the filling bars being thus locked against any transverse movement, while being allowed to slide in the grooves *e*. At the edge where 5 they come into contact with the cops, they present a shape *f*, *g*, *h*, *i*, *k*, *l*, *m* exactly adapted to the outline of the cop layers along their rows. This particular shape 10 of the filling bars ensures the position of the cops in their longitudinal direction during the treatment. When the container *a* is of relatively great width, it is advantageous to separate each layer of cops into two or more sections (Fig. 4) and to insert 15 between them filling bars *b*², *b*³ of the kind represented at I and II in Fig. 6, the bars *b*², *b*³ alternating in the successive layers as shown in Fig. 4 by full and dotted lines. After the pack in the container *a* being 20 completed, the whole is compressed transversely to the longitudinal axis of the cops until the superimposed filling bars enter in contact with one another (Fig. 3), so that all passages between the cops as well as the 25 openings of the cop tubes are tightly closed. This tight packing insures a uniform im-

pregnation throughout of the cops in all the layers of the container.

What I claim is:

In an apparatus for packing cops to be 30 impregnated with a dyeing, bleaching or other liquid, the combination of a pack container with side filling bars arranged along the sides of the container and so shaped in cross section as to closely contact 35 with the sides of the cop layers, in order to close up dead spaces along the same, said container being provided on the inner side of its front walls with guide means to receive end parts of said filling bars for locking same.

In witness whereof I have hereunto signed my name this 19th day of December 1923, in the presence of two subscribing witnesses.

DR. ALFRED RESCH,
Administrator of the estate of Wilhelm Resch, deceased.
